UNITED STATES PATENT OFFICE.

NIELS WALTERSEN AASEN, OF CHRISTIANIA, NORWAY.

DEVICE FOR SHOOTING GRENADES.

1,309,791.

Specification of Letters Patent. Patented July 15, 1919.

Application filed December 8, 1917. Serial No. 206,170.

To all whom it may concern:

Be it known that I, NIELS WALTERSEN AASEN, a subject of the King of Norway, residing at Christiania, in the Kingdom of Norway, have invented certain new and useful Improvements in Devices for Shooting Grenades; and I do hereby declare the following to be a full, clear, and exact description of the invention, such as will enable others skilled in the art to which it appertains to make and use the same, reference being had to the accompanying drawings, and to letters or figures of reference marked thereon, which form a part of this specification.

This invention relates to a device for shooting grenades of the kind which consists of a grenade throwing tube fixed to an ordinary rifle and connected with its back end by means of a channel to the bore of the rifle.

According to the present invention the channel connecting the back end of the grenade throwing tube with the bore of the rifle is provided with an adjusting cock or valve by means of which the cross section of the channel may be throttled or the channel completely closed.

The invention also comprises a number of improvements in devices of the kind above referred to which will be more particularly described in the following specification.

On the drawing:

Figure 1 is a longitudinal section through a form of the invention mounted on a rifle.

Fig. 2 is a section on the line II—II of Fig. 1 and

Fig. 3 is a longitudinal section of a modified form of the invention.

The grenade throwing apparatus consists of a cylinder 1 which is fastened in a known manner to the rifle barrel and communicates with the bore of the same by means of a channel 2.

In order to regulate the cross section of this channel and thereby adjust the range of the grenade thrower the same according to the present invention is provided with a throttle valve consisting of a screw 3 by means of which the channel 2 may be wholly or partly closed. When the channel is completely closed the rifle may be used in the ordinary manner without the grenade shooter causing any noticeable inconvenience.

In order to spread the explosion gases over

the back end surface of the grenade a deflecting piece 4 is mounted in front of the channel opening, said deflecting piece having a wedge shaped cross section as seen on Fig. 2.

The grenade may be of any convenient form but in any case it is preferred to provide the same with a guiding sleeve 5, which is so formed that it keeps the back end of the grenade at some distance from the back end of the tube 1 thereby forming a chamber which is filled with pressure gas at the moment when the opening of the channel 2 into the bore of the rifle is uncovered by the bullet. Said guiding sleeve 5 is pressed with its walls against the inside of tube 1, thus serving also to tighten the grenade in the throwing tube. The guiding sleeve is provided with an annular groove 6 which serves to prevent the sticking of the grenade in the tube 1.

As illustrated on Fig. 3 the channel 2 may be provided with a nonreturn valve 7 with the object of preventing the escape of pressure gas from tube 1 after the bullet has passed out of the rifle barrel. Said nonreturn valve 7 may consist of a ball valve as indicated on the drawing or of any other known and suitable form of valve.

I claim:

1. Grenade throwing device for rifles comprising a grenade throwing tube, a channel connecting the back end of said grenade throwing tube with the bore of the rifle and means for throttling or closing the said channel in order to regulate the range of the grenade throwing device.

2. Grenade throwing device for rifles comprising a grenade throwing tube, a channel connecting the back end of said grenade throwing tube with the bore of the rifle, means for throttling or closing the said channel in order to regulate the range of the grenade throwing device and a nonreturn valve in the channel for preventing the escape of gas into the rifle bore after the bullet has passed out of the same.

3. Grenade throwing device for rifles comprising a grenade throwing tube, a channel connecting the back end of said grenade throwing tube with the bore of the rifle and a screw valve for regulating the cross section of said channel.

4. Grenade throwing device for rifles comprising a grenade throwing tube, a channel connecting the back end of said grenade

- throwing tube with the bore of the rifle, means for throttling or closing the said channel in order to regulate the range of the grenade throwing device and a deflector in the back end of said tube for distributing the pressure evenly over the back end of the grenade.
5. Grenade throwing device for rifles comprising a grenade throwing tube, a channel connecting the back end of said grenade throwing tube with the bore of the rifle and
- 10

a grenade comprising a cupshaped guiding sleeve with its open end turned backward in order to give room for a certain volume of pressure gas behind the grenade.

15

In testimony that I claim the foregoing as my invention, I have signed my name in presence of two subscribing witnesses.

NIELS WALTERSEN AASEN.
